UNITED STATES PATENT OFFICE.

HARRY K. RAYMOND, OF AKRON, OHIO, ASSIGNOR TO THE B. F. GOODRICH COMPANY, OF AKRON, OHIO, A CORPORATION OF OHIO.

INNER TUBE OF PNEUMATIC TIRES.

No. 931,648.

Specification of Letters Patent.

Patented Aug. 17, 1909.

Application filed April 16, 1909. Serial No. 490,255.

To all whom it may concern:

Be it known, that I, HARRY K. RAYMOND, a citizen of the United States, residing at Akron, in the county of Summit and State 5 of Ohio, have invented certain new and useful Improvements in Inner Tubes of Pneumatic Tires, of which the following is a specification.

My invention pertains to improvements 10 in pneumatic tires, and relates more specifically to the construction of the inner inflatable tube.

The invention is illustrated in the annexed drawings, wherein:

15 Figure 1 is a sectional elevation of a tire, the outer casing being shown in section and the inner tube in elevation; Fig. 2 a perspective view of the inner tube in its deflated condition; Fig. 3 a longitudinal sec- 20 tional view of the abutting and overlapping ends of the inner tube; Fig. 4 a transverse sectional view, taken on the line 4—4 of Fig. 3; and Fig. 5 a longitudinal sectional view, showing a modification of the invention.

25 The tube forming the basis of the present invention is of the overlapping-end type, such, for instance, as those shown in United States Letters Patent to Morgan & Wright, Nos. 502,047 and 502,048, dated July 25, 30 1893, wherein the member of which the tube is formed is closed for a distance from each end, the closed portions overlapping the main body of the tube when the same is positioned within the outer casing and the 35 tube inflated.

The main object of the present invention is to provide a fastening device or devices for the overlapping ends of the tube, so as to hold said ends in their proper relation to 40 each other and to the body of the tube and thus prevent the tube from becoming twisted when placed within the outer casing.

In the drawings, Figs. 1 to 4 inclusive, 1 indicates the main body of the inner tube, 45 the ends 2 and 3 of which are flattened and permanently closed by vulcanizing together the opposite portions of the tube which are brought into contact with each other. The flattened portion 2 is provided with an eye- 50 let 4 through which a valve-stem 5 is passed when the parts are to be positioned within the inner casing.

In order to strengthen the end 2 of the tube, a strip of canvas or similar textile

material, 6, will be secured to said portion 55 prior to passing the eyelet 4 therethrough, said strip, as will be seen upon reference to Figs. 1 and 3, underlying the point where the edges of the outer casing come together, thus preventing the flattened end from being pinched by the outer casing when the same is drawn together in the act of securing it upon the rim or wheel. The opposite flattened end 3 is provided with a button-hole or opening 7, said hole being reinforced 60 by a piece of canvas 8, vulcanized or otherwise secured upon the outer face of said flattened portion. A button preferably hav- 65 ing a flexible head 9 and preferably a flexible shank 10, is secured to the body of the 70 tube at a point opposite the button-hole, when the tube is in its normal position, or in other words, when the valve-stem 5 is passed through the eyelet, and the length of 75 the tube is equal or approximately equal to the dimensions of the outer tube or casing in which it is to be placed. The shank 10 is preferably formed with a base-piece 11 of rubber, said base piece being solutioned or vulcanized to the body of the tube so that 80 it becomes in effect an integral portion there- 85 of. Thus it will be seen that when the head of the button is passed through the button-hole, the end 3 will be secured to the body of the tube, and this fastening, acting in conjunction with the valve-stem, which holds the other end of the tube, prevents the tube from becoming twisted and enables the same to be readily positioned within the outer 90 casing. The button and its shank, in the preferred form, together with the base, being flexible, and the end 3 being likewise flexible, the parts readily conform to the casing when the tube is inflated.

The present type of tube is particularly 95 useful in motor cycles, the chief advantage being that in order to insert a new tube the wheel does not have to be removed from the frame, as is the case where a complete annular tube is inserted in the outer casing.

100 In inserting tubes of the character herein set forth, in which one end of the lap is free, considerable difficulty has been experienced in keeping the tube straight and preventing it from twisting, as must be done in order to give efficient service. The provision of the button or some similar fastening device for the ordinarily free end

of the lap makes it easier to insert the lapped portions of the tube and aids in securing the desired result.

By the employment of a flexible fastening 5 for the overlapping end of the inner tube which bears against the inner portion of the casing next adjacent to the tread thereof, no lump or projection will be formed upon the casing or the tread thereof when the tire 10 is inflated. In other words, the flexible or yielding fastening device conforms to the inner portion of the casing.

While I have described the valve stem as forming a means for securing one end of the 15 tube in place upon the body of the tube it will be readily appreciated by those skilled in the art, that such attachment is not of the essence of the present invention; in fact in so far as the generic invention is concerned 20 such arrangement of the valve stem may be omitted and, if desired, both ends of the tube may be secured by buttons and the valve stem placed elsewhere. Such construction is shown in Fig. 5, the buttons 25 and allied parts being of the same form as those shown in the other figures and having, consequently, the same reference numerals.

Having thus described my invention, what I claim is:

30 1. An inner tube for inflatable tires, comprising a hollow body having closed ends, said ends being adapted to overlap each other and the body portion of the tube; a valve-stem extending from the body and 35 adapted to pass through an opening formed in the adjacent end of the tube; and means for securing the opposite end to the body of the tube.

2. An inner tube for inflatable tires, comprising a hollow body portion having closed 40 flattened ends, said ends being adapted to overlie each other and a portion of the body, one end being formed with a button-hole; and a button secured to the body of the 45 tube, adapted to be passed through the button-hole.

3. An inner tube for inflatable tires, comprising a hollow body portion having closed 50 flattened ends adapted to overlap, one of said ends being provided with a button-hole; and a flexible button secured to the body of the tube and adapted to be passed through the button-hole.

4. An inner tube for inflatable tires, comprising a hollow body portion having closed, flattened ends, one of said ends having a 55 button-hole formed therein; a reinforcing member secured to said end and surrounding the button-hole; and a flexible button secured to the body of the tube and adapted to be passed through the button-hole.

5. An inner tube for inflatable tires, comprising a hollow body portion having flattened, closed ends; an eyelet placed in one of said ends; a valve-stem secured to the 60 body of the tube and adapted, when the tube assumes an annular form, to be passed through said eyelet; and a flexible button secured to the body of the tube and adapted to be passed through a button-hole 70 formed in the other flattened end.

6. An inner tube for inflatable tires, comprising a hollow body portion having flattened, closed ends; an eyelet placed in one of said ends; a valve-stem secured to the body 75 of the tube and adapted, when the tube comes to annular form, to be passed through said eyelet; a flexible button secured to the body of the tube and adapted to be passed through a button-hole formed in the other 80 flattened end; and a strengthening member secured to said last-mentioned flattened end upon one face thereof, and adapted to reinforce the button-hole.

7. An inner tube for inflatable tires, comprising a tubular member having flattened, closed ends; and flexible means for securing an interlocking connection between one of said ends and the body of the tube when 85 said end is overlapped onto the body.

8. An inner tube for inflatable tires comprising a tubular member having closed ends said ends adapted, when the tube is positioned, to overlap upon the body of the tube; means for securing one of said ends in position upon the body; and independent flexible means for securing an interlocking connection between the other end of the body 95 of the tube.

9. In a tire the combination of a casing; 100 an inner tube having closed ends adapted to overlap the body of the tube when the same is positioned within the casing; and means for securing that end of the tube which lies next adjacent to the tread section of the 105 casing to the tube.

10. In a tire the combination of a casing; an inner tube having closed ends adapted to overlap the body of the tube when the same is positioned within the casing; and flexible 110 or yielding means for securing that end of the tube which lies next adjacent to the tread section of the casing to the tube, whereby said means will conform to the casing without distorting the latter.

In testimony whereof I have signed my name to this specification in the presence of two subscribing witnesses.

HARRY K. RAYMOND.
